UNITED STATES PATENT OFFICE.

ARTHUR C. MASON AND ALFRED T. STURT, OF FLINT, MICHIGAN, ASSIGNEES TO CHEVROLET MOTOR COMPANY, OF NEW YORK, N. Y., A CORPORATION OF DELAWARE.

PISTON.

1,275,064.

Specification of Letters Patent.

Patented Aug. 6, 1918.

Application filed July 26, 1916. Serial No. 111,474.

To all whom it may concern:

Be it known that we, ARTHUR C. MASON and ALFRED T. STURT, citizens of the United States, and residents of the city of Flint, county of Genesee, and State of Michigan, have jointly invented certain new and useful Improvements in Pistons; and we do hereby declare the following to be a full, clear, and exact description thereof.

10 This invention relates to the construction of pistons designed primarily for use in internal combustion engines. The object of the invention is to so form and construct a piston that it will be capable of expansion 15 due to the heat in the cylinder of an internal combustion engine, and at the same time eliminate the danger of scoring the cylinder wall especially at points adjacent to the piston pin holes, which is a more or less 20 frequent occurrence in engines of this type of different construction. To this end I construct a piston the skirt of which in horizontal section is substantially elliptical in shape, the minor axis being in line with 25 that of the piston pin, and the major axis being perpendicular thereto. The ring groove flanges, and the piston head are substantially circular in cross-section, the diameters of which are slightly less than the 30 length of the minor axis of the section of the skirt. The diameters of the ring groove flanges in practice grow gradually less from the flange nearest the skirt to the head of the piston.

In practice, a piston, the skirt of which has a major axis equal to 3.685" is provided with a minor axis of .003" to .005" less in length than the major axis.

We find that a very efficient construction is to cause each radius of the minor axis to be .002" less in length than the radius of the major axis.

Referring to the drawings in which the same reference character indicates the same part in the several views:

Figure 1 is a section of a piston and connecting rod, the connecting rod being shown in elevation.

Fig. 2 is an end view of the piston looking in the direction of the arrow in Fig. 1.

Fig. 3 is an end view of a piston looking in the direction of the arrow of Fig. 1, said piston being mounted in the cylinder, the position of the piston in the cylinder being

merely conventionally shown in extreme proportion in the interest of clearness. 55

The part marked 1 is the piston, 2 the connecting rod and 3 the piston pin, said connecting rod being secured to the pin by the usual split collar 4 with a screwthreaded bolt 5, the piston pin being mounted in the sleeves 6 and 6'. 7 is the cylinder, the inner wall of which is truly cylindrical. The major axis of the skirt 9 of the piston lies between the lines *a*—*b*, and the minor axis lies between the lines *c*—*d*. The piston fits the cylinder at the extremities of the major axis with a conventional working clearance at X and Y, so that the piston will be guided truly in the cylinder during its 70 reciprocation therein, as clearly shown in Fig. 3.

The sides of the piston in line with the axis of the piston pin are at the extremities of the minor axis of the ellipse. 75

While the horizontal cross section of the skirt of the piston is in theory in the form of an ellipse, yet we wish it to be understood that if for any reason the relation of the minor axis to the major axis of the cross-section, is such as to form a shape or curve which is not a true mathematical ellipse, still such a form would be within the scope of our invention. 80

As hereinbefore described, the showing in Fig. 3 of the relative dimensions of the piston and cylinder is merely conventional and greatly enlarged so as to more clearly illustrate the construction. 85

The ring groove flanges 10, 11 and 12 are 90 in plan and in horizontal cross-section true circles, the diameters of which, due to the fact that the head is subjected to the most heat, are less than the length of the minor axis of the horizontal section of the skirt 9, 95 and the diameter of the head 12 is slightly less than that of the flange 11, and the diameter of the flange 11 is slightly less than that of the flange 10.

By providing a piston the skirt of which 100 is substantially elliptical in cross-section, we find in practice that the danger of scoring the cylinder due to unequal expansion, by reason of the heat to which the metals of the piston and of the cylinder are subjected, is 105 reduced to a minimum and is in effect *nil*.

In operation, the thrust of the piston at the points X and Y upon the surface of the

cylinder is resisted by the cylinder wall and as a result of this action a distortion, both of the piston and the cylinder wall takes place, so that the piston is expanded along 5 its minor axis and the diameter of the cylinder in line with the minor axis of the piston is to some degree lessened, thereby enlarging the area of the surface contact of the piston and cylinder wall at the extremities 10 of the major axis of the piston.

This construction produces a contact of the piston with the cylinder wall, which at all times is stable and the bearing is thus caused to widen as the piston is subjected to 15 greater loads, and the piston and cylinder to greater heat, thereby causing an additional bearing surface, to compensate for the additional load on the piston, and the danger of scoring the cylinder wall is thus 20 avoided.

As changes could be made within the scope of our invention, we intend that all matter contained in the above description or shown in the accompanying drawings shall 25 be interpreted as illustrative and not in a limiting sense.

Having now described our invention, what we claim as new and desire to secure by Letters Patent is:

30 1. An engine piston substantially elliptical in horizontal cross section in combination with a cylinder, having a substantially circular cross section.

2. An engine piston, the horizontal cross 35 section of which is provided with a major and minor axis in combination with a cylinder having a substantially circular cross section.

3. A piston, as set forth in claim 1, in 40 which the piston pin is substantially parallel with the minor axis.

4. The combination of an engine cylinder and its piston, said piston having major and minor axes in the horizontal cross-section 45 thereof to provide clearance spaces between the piston and the portions of the wall of the cylinder opposite the extremities of the said minor axis.

5. An engine piston having a continuous 50 or unbroken wearing surface whose diameter in one direction slightly exceeds the diameter at right angles thereto, both of said diameters lying in the same plane.

6. The combination with a cylinder of a piston therein, the horizontal section of 55 which is substantially in the form of an ellipse, the major axis of said ellipse being substantially equal to the diameter of the cylinder.

7. A piston, provided with a head having 60 ring groove flanges, and a skirt, the said flanges being substantially circular in horizontal cross-section, and the skirt being substantially elliptical in horizontal cross-section. 65

8. A piston as set forth in claim 7, in which the diameter of the cross section of the circular portion is less than the minor axis of the ellipse, the major axis of the ellipse being substantially equal to the diameter 70 of the cylinder.

9. A piston as set forth in claim 8, in which the ring groove flanges have decreasing diameters, the flange of largest diameter 75 being closest to the skirt.

10. A piston provided with a head having ring groove flanges, and a skirt, the said flange being circular in horizontal cross-section, and the skirt being elliptical in horizontal cross-section, the diameter of the circular cross section being less than the minor axis of the ellipse. 80

11. A piston provided with a head and skirt, the head being circular in horizontal cross-section and the skirt being elliptical in 85 horizontal cross-section, the diameter of the circular cross-section being no longer than the length of the minor axis of the ellipse.

12. The combination of a piston and an engine cylinder, one of which is substantially elliptical in horizontal cross-section, and the other of which is substantially circular in horizontal cross section. 90

13. In combination, an inclosing envelop and an inclosed piston, the horizontal cross 95 section of the two being of substantially different area and shape, respectively.

In witness whereof we have hereunto set our hands at the borough of Manhattan, city, county, and State of New York, this 100 10th day of July, 1916.

ARTHUR C. MASON.
ALFRED T. STURT.

In presence of—

ISABEL R. RICHARDS,
ETHEL D. BAWN.
